UNITED STATES PATENT OFFICE.

GEORGE F. NELSON, OF WASHINGTON, DISTRICT OF COLUMBIA, ASSIGNOR TO HENRY MAY, OF WASHINGTON, DISTRICT OF COLUMBIA.

BOTARY PUMP AND MOTOR.

1,098,458.

Specification of Letters Patent. Patented June 2, 1914

Application filed November 18, 1910. Serial No. 593,079.

To all whom it may concern:

Be it known that I, GEORGE F. NELSON, a citizen of the United States, residing at Washington, in the District of Columbia, have invented a new and useful Improvement in Rotary Pumps and Motors, of which the following is a specification.

This invention is a new and useful construction of rotary pump and more particularly an improvement upon the rotary pump patented to McLean, Lyons, and Clark, Numbers 904,209, and 940,817.

This improvement can also be utilized as a motor either of the air or water type and the invention is also capable of use as an air compressor and as a matter of fact the device can be used as a pump and compressor, or a motor and compressor or the device can be used as a combined motor, pump and compression or suction apparatus.

The object of my invention is to provide a simple and efficient construction of rotary pump in which the pressure upon opposite sides of the piston will be substantially equalized or balanced and a still further object is to provide a combined sealing and lubricating means and another object is to provide for the adjustment or shifting of the movable piston from the exterior of the device, thereby avoiding the necessity of opening the casing for the purpose of effecting such adjustment.

Another object of the invention is to provide exterior connections whereby fluid can be transferred from one ring or stage to another ring or stage, and these exterior connections also enable various combinations to be effected.

Another object of the invention is to provide for the intake and discharge of the fluid at various points thereby avoiding the possibility of a dead center.

With these various objects in view and also certain other objects as will appear hereinafter, my invention consists in the various novelties of construction and also the novel manner of combining or arranging the parts all of which will be fully described hereinafter and pointed out in the claims.

In the drawings forming a part of this specification: Figure 1 is a perspective view of a pump or motor constructed in accordance with my invention. Fig. 2 is a vertical sectional view, the dividing wall or partition being omitted. Fig. 3 is a top plan

view, the cover and piston being removed. Fig. 4 is an inverted plan view of the piston. Fig. 5 is a top view of the piston. Fig. 6 is a side elevation of the piston. Fig. 7 is an inverted plan view of the top of the casing. Fig. 8 is a detail perspective view of the rotary shaft. Fig. 9 is a top view of the eccentric bushing. Fig. 10 is a side view. Fig. 11 is a detail perspective view of the sliding block carried by the piston. Fig. 12 is a top plan view of a slightly modified form of head or cylinder, the partition walls being arranged at various points in order to prevent a dead center. Fig. 13 is a sectional plan showing the arrangement of the ports and passages. Fig. 14 is an inverted plan view of the piston adapted to be used in connection with the cylinder or casing shown in Fig. 12. Figs. 15, 16, 17, 18, and 19 are diagrammatic views showing the manner of arranging the exterior connections whereby various combinations are obtained.

In carrying out my invention I prefer to arrange the device horizontally upon a base A, but it will of course be understood that it can be arranged in any position desired. In practice the base A is formed with legs or standards B, which support the cylinder or casing C, which is formed with a circular chamber provided with a series of concentric rings C' extending upwardly as shown, said rings being united to a partition or dividing wall C². These series of rings C' provide a series of concentric passages C³ and a central chamber C⁴ and ports C⁵ communicate with the passages C³ upon one side of the partition C² while ports C⁶ communicate with the passages C³ upon the opposite side of said partition C², said ports extending downwardly through the base and having their exit in the base portion B' as most clearly shown.

C⁷ indicates a water passage for the purpose of keeping the device cool, water being introduced through the pipes C⁸ and circulated around the casing.

The piston D comprises a circular plate D' provided with a series of concentric rings D² divided at D⁶ to receive the partition C² and this plate D' is also provided with a depending socket or recessed portion D⁴ which works within the central chamber C⁴ of the cylinder C. It will of course be understood that there will be as many rings 110

D² as there will be passages C³ and the width of the opening D³ will in a measure depend upon the use to which the device is to be put, as it will be understood that this pump 5 can be utilized for pumping either oil, water, air, or sand, or a mixture of any liquid, and granular material.

E indicates the upper portion or cover of the casing being secured to the cylinder C by 10 means of bolts E'. This upper portion or cover E is made with considerable thickness at the center in order to provide a suitable bearing for the shaft F, said shaft having a collar F' adjacent its lower end and which 15 is adapted to fit in a circular recess F² formed centrally in the underside of the cover E and this shaft terminates in an eccentric stub shaft F³, upon which is arranged the eccentric bushing F⁴, said bushing fitting snugly within the socket D⁴ of the piston. This eccentric bushing is secured by 20 means of a bolt F⁵ threaded into the bottom of the bushing as shown at F⁶, said bolt extending upwardly through the shaft F and 25 fastened by means of a nut F⁷. By means of this construction the nut can be loosened and the bolt F⁵ turned in either direction for the purpose of adjusting the position of the bushing upon the eccentric end of the shaft 30 whereby the throw of the piston can be adjusted and after the bushing has been adjusted the nut F⁷ is tightened and the bushing will be locked firmly upon the end of the shaft.

35 It will thus be seen that I provide for the adjustment of the parts without necessitating the opening of the cylinder or casing. Any suitable form of wheel or pulley can be connected to the upper end of the shaft 40 F for the purpose of imparting a rotary motion and in the drawings I have shown a hand wheel F⁸ so constructed as to be coupled or connected with any rotating member. It will be understood that as the shaft F 45 is rotated the piston will be given an eccentric oscillating movement so that the ring portions D² will be caused to approach and recede from the ring portions C³, constantly providing sector shaped chambers into 50 which fluid is drawn at one end and discharged at the other. The ports C⁵ we will designate as inlet ports and the ports C⁶ as exhaust ports and it will therefore be understood that the liquid is drawn up through 55 the ports C⁵ carried around the channels or passages C³ and discharged at the ports C⁶, or the operation can be exactly the reverse. The cover E is formed with a recess G oval in shape and in which works a sliding block 60 G', having an opening G² which receives the pin G³ formed upon the plate D', said block serving to guide the movement of the piston and prevent the ends of the rings coming in contact with the partition wall. The cover 65 E is also provided with an inlet passage H,

to which a connection pipe H' is attached for the purpose of applying oil under pressure upon the top side of the piston and inasmuch as a constant pressure will be maintained upon the said top side of the 70 piston the oil will be forced into contact with the moving parts and said parts will not only be sealed but also lubricated and consequently the liquid being drawn or forced through the device will not be able 75 to work past the piston.

By employing a plurality of rings I am able to convey the liquid from one ring or stage to another ring or stage and by referring to Fig. 1 it will be noted that I is the 80 intake pipe, which enters the lowest port and which communicates with the innermost ring and the liquid so introduced carried around and discharged from the lowermost port into a connecting pipe K, which 85 extends from the lowermost port on one side to the next higher port on the opposite side, and from there the liquid is carried around and discharged from the port opposite into the connecting pipe K' and after being carried around, is discharged through the outlet or discharge pipe I'. Connecting the outlet or discharge pipe I' is a pipe L, which extends from the outlet pipe I' to the connecting pipe K and is provided with valves 90 L' upon opposite sides of a central connection L² which in turn carries a gage and is connected with the pressure connection H'. By the proper manipulation of the valves L' the pressure upon the top side of the piston 100 can be made to balance the pressure upon the lower side of said piston thereby providing a perfectly balanced piston whereby the pressure or friction is reduced to a minimum and the efficiency of the pump correspondingly increased.

Now it will be understood that the exterior connections I and I', K and K', and pipe L can be changed or shifted as desired in order to provide for the various operations of the device and in Fig. 15 I have shown a diagram of the construction illustrated in Fig. 1, whereas in Fig. 16 air is taken in at the first stage and discharged through the third stage and the second ring 110 115 or stage is utilized for the purpose of operating the air suction and discharge, the water serving as a motive power. In Figs. 17, and 18, I have shown other forms of connection in which the pressure pipe is connected at various points and in Fig. 19 I have shown the pressure pipe connected with the connection pipes in series, check valves being arranged to prevent back pressure.

In Figs. 12 and 14 it will be noted that the 125 partition walls C¹⁰ are arranged alternately at different points, in the present instance at angles of 90 degrees but it will of course be understood that they can be arranged at any angle desired, and the openings in the 130

piston rings are correspondingly arranged. The ports are arranged upon opposite sides of the partitions but it will be noted that the ports communicate with alternate rings corresponding with the alteration of the partitions and by means of this construction liquid can be taken from the exterior port C¹¹ and discharged in compressed form through the interior port C¹² or the reverse operation can take place. By means of this construction I can provide a simple and efficient form of air compressor or vacuum producer according to the direction of motion and it will also be understood that by arranging the partitions in alternating and broken joint form I completely overcome the danger of the dead center.

It will thus be seen that I provide a simple and efficient form of device which can be used as a pump or a motor or both combined and which will carry out all of the objects hereinbefore referred to.

It will be understood that this invention is susceptible of a variety of changes or alterations without departing from the broad principle of the invention and consequently I do not wish to be confined to the exact features of construction and combination herein shown and described.

Having thus fully described my invention, what I claim as new and desire to secure by Letters Patent, is:

1. In a device of the kind described, a casing provided with a concentric passage having ports communicating therein, a piston provided with a divided concentric ring and having a central socket, a rotary eccentric fitting in said socket and adapted to impart an oscillatory motion to said piston, a bushing arranged within the socket and surrounding the eccentric and a rod rigidly connected to said bushing and working through the eccentric, said rod being adjustable for the purpose of adjusting the bushing, as set forth.

2. In a device of the kind described, a casing having a concentric passage having ports communicating therewith, a piston having a concentric divided ring and a central socket, a rotary eccentric for imparting an oscillatory motion to said piston, a bushing surrounding said eccentric, means for adjusting said bushing, together with means for introducing pressure upon the rear side of the piston.

3. In a device of the kind described, a casing having concentric passages, a piston having concentric rings, means for imparting an oscillatory movement to said piston together with means for applying liquid pressure upon the upper side of said piston.

4. In a device of the kind described, the

combination of a casing and piston, said casing having inlet and outlet ports, exterior connections connected with said ports, and a connection between one or more of the exterior connections and the upper side of the piston, as set forth.

5. In a device of the kind described, the combination with the casing and piston and cover, means for imparting motion to the piston, said casing having inlet and outlet ports, exterior connections connected with said ports, a pressure pipe leading into the cover, and a connection between said pressure pipe and the exterior connections as set forth.

6. The combination with the casing, piston, and cover together with means for operating the piston, said casing having inlet and exhaust ports, a pressure pipe leading into the cover and a pipe connecting said pressure pipe with the exterior connections, said pipe having one or more valves for the purpose specified.

7. In a device of the kind described, the combination with a casing having a plurality of concentric passages, each passage having a partition, the alternate partitions being arranged out of alinement, of a piston having a plurality of concentric rings, each ring being divided at one point, the alternate division points being out of alinement, for the purpose specified.

8. In a device of the kind described, a casing having a plurality of concentric passages having inlet and outlet ports communicating therewith, of exterior connections connected with said ports, a piston having concentric rings, a cover, a shaft working in said cover and adapted to impart an oscillating movement to the piston, a pipe connecting the exterior connections, valves carried by said pipe and the connection between said pipe and the pressure pipe, substantially as described.

9. In a device of the kind described, the combination with the casing, piston, cover and operating means constructed as described, said casing having inlet and outlet ports, the cover being provided with a connection whereby pressure can be applied to the upper side of the piston, exterior connections connected with the inlet and outlet ports, said exterior connections being interchangeable or adjustable and a pipe connected with the pressure pipe and connecting the exterior connections upon the inlet and outlet sides whereby pressure upon the piston is balanced or equalized as set forth.
